TREATMENT OF PETROLEUM PRODUCTS

Alexander N. Sachanen and Rowland C. Hansford, Woodbury, N. J., assignors to Socony-Vacuum Oil Company, Incorporated, New York, N. Y., a corporation of New York

No Drawing. Application January 20, 1939,
Serial No. 251,914

3 Claims. (Cl. 260—672)

This invention relates to the production of aromatic compounds from petroleum products. More particularly the invention relates to a process for the use of certain petroleum products in the production of alkyl benzenes and alkyl naphthalenes of low molecular weight.

Of late years the alkyl-substituted aromatic compounds of relatively low molecular weight have become of increasing importance, e. g., as solvents, and especially as gasoline additive agents because of their high anti-knock characteristics. As a result of this increased importance of the alkyl-substituted aromatic compounds various processes have been suggested for their preparation. However, so far as is known, no one has touched upon our novel process of using certain petroleum products in the preparation of these compounds.

It is an object of this invention to provide a process for the preparation of valuable aromatic compounds with the use of petroleum products.

A more specific object of the invention is to provide a process for treating certain petroleum products, including waste hydrocarbon by-products of petroleum refining, whereby substantial yields are obtained of benzene and naphthalene derivatives.

Still another specific object of the invention is to provide a process for treating certain petroleum products, including hydrocarbon by-products of petroleum refining, whereby substantial yields are obtained of aromatic compounds boiling within the gasoline boiling range, as well as substantial yields of alkyl benzenes and alkyl naphthalenes boiling up to about 300° C.

Our invention is based upon the discovery that certain petroleum products may be treated with benzene at relatively low temperatures of the nature herein disclosed in the presence of suitable catalysts to produce substantial yields of valuable benzene and naphthalene derivatives.

The reactions which appear to be involved in our process comprise the transfer of side chains from various complex molecules of the petroleum product to the molecules of the admixed benzene. This results in a consumption of benzene. The consumption of benzene may or may not be nearly equivalent to the amount of the newly formed alkyl benzenes, depending on the quantity of more or less highly alkylated benzenes in the petroleum stock which may be sufficiently dealkylated to give an additional amount of lower boiling alkyl benzenes. High boiling alkyl naphthalenes initially present in the petroleum stock are converted to lower boiling alkyl naphtha-

lenes by this process of transfer of side chains to benzene. No alkyl aromatics are obtainable from the purely naphthenic products in the petroleum stock except those alkyl benzenes produced by the alkylation of benzene by side chains transferred from the alkyl naphthalenes. Under the conditions of the present process no appreciable dehydrogenation of naphthalenes to aromatics is possible. This is in contrast to our high temperature dealkylation process for these same petroleum stocks disclosed and claimed in the co-pending application S. N. 227,977, filed September 1, 1938, now U. S. Patent 2,223,133, issued November 26, 1940.

It has been known to dealkylate synthetic alkyl benzenes heretofore, however such prior processes are to be clearly distinguished from the present important discovery. The known dealkylation of alkyl benzenes has been carried out on relatively simple synthetic alkyl benzenes formed by alkylating benzene with olefines. On the other hand we have discovered certain industrial petroleum products as, for instance, complex industrial by-products such as solvent tars from the solvent refining of petroleum oils or the cracked residuum from petroleum cracking processes which may be treated to effect a dealkylation of the various more or less complex molecules therein. In the present process not only simple alkyl benzenes but also alkyl derivatives of rather complex polycyclic aromatic hydrocarbons as well as those of naphthenic hydrocarbons are subjected to dealkylation. Moreover, by our process not only is a substantial yield of alkyl benzenes in the gasoline boiling range obtained, but also a substantial yield of alkyl benzenes and alkyl naphthalenes boiling below about 300° F. is obtained. Quite obviously no alkyl naphthalenes are produced by the known dealkylation process above mentioned.

That a sharp distinction exists between the present process and the above-mentioned prior art processes is established perhaps most clearly by the fact that sulfuric acid, which is disclosed as an effective catalyst for these prior art processes, cannot be used as a catalyst in our process.

As sources of petroleum material to be treated by our process, we wish to call particular attention to solvent tars which, as is well known, are the by-product from the present-day solvent refining processes of petroleum. Accordingly, by our process we not only afford means of obtaining extremely valuable aromatic products but also afford a use for a material which is now usually considered a waste by-product of the

petroleum industry. In addition to the solvent tars, it is to be clearly understood that the present process is applicable to the treatment of many other petroleum products and in fact is applicable to the treatment of any petroleum product containing substantial amounts of aromatic or naphthenic hydrocarbons. For instance, the petroleum products containing a considerable amount of aromatic or naphthenic hydrocarbons which are to be treated may include petroleum residues such as solvent and cracking tars and straight run residua. Moreover high boiling distillates (including distillates from tars) may be treated. The distillates may be any distillates boiling in the range of kerosene or higher and containing substantial amounts of aromatic or naphthenic hydrocarbons. Some specific examples of petroleum material suitable for treating, which are mentioned here merely for illustrative purposes, include Mirando, Rodessa, and East Texas furfural solvent tars from neutrals (distillates of lubricating oil fractions), Pennsylvania chlorex solvent tar from neutrals, dewaxed distillates, burning and power kerosene distillates, naphthenic distillate for cracking, distillate from an Ellis (coil and drum) cracked residuum and an Ellis cracked residuum. For the best yields it is desirable to use petroleum products containing a predominant portion of aromatic or naphthenic hydrocarbons. Petroleum products containing less amounts may be used but the yields are correspondingly less.

The catalytic material to be used in our process must be capable of promoting dealkylation reactions of our petroleum products under the conditions of the process. Catalysts of the nature of heavy metal halides as, for example aluminum chloride, aluminum bromide, zirconium chloride and zinc chloride are suitable. In our preferred operation we employ aluminum chloride as the catalyst. However, it is to be noted particularly, as mentioned hereinabove, that an acid catalyst such as sulfuric acid is not operative in the present process, it having been found that sulfuric acid has a negative effect in the dealkylation of petroleum products according to our process.

For best results the temperatures employed in our process should be effective operating temperatures which are below about 400° F. and preferably between about 175° F. and about 250° F. In the preferred form of the invention, using aluminum chloride as a catalyst, we consider a temperature around 180° F. to be the most desirable.

From a practical standpoint we have found a ratio of benzene to stock treated of about ½ volume to 2 volumes of benzene to 1 volume of stock usually gives proper proportioning for obtaining our desired results. It is to be understood, however, that the invention is not limited

to these ratios but rather contemplates the broad use of benzene in any amount sufficient to give our novel results.

The invention may be further illustrated by the following data obtained from the treatment of a Mirando furfural solvent tar with benzene. It is to be understood that these specific treatments are not to be considered limiting as there may be variations therefrom without departing from the scope of the invention. The reaction mixture in both treatments comprised 1 part Mirando furfural tar, 2 parts benzene and 10% aluminum chloride. It is to be noted that this Mirando tar did not contain initially any distillates boiling below 315° C.

Reaction temp., °F.	Reaction time in hrs.	Alkylated benzenes 100-200° C.		Alkylated aromatics 200-300° C.		Residuum 300° C.		Recovered benzene to 100° C.
		Per cent	Sp. gr.	Per cent	Sp. gr.	Per cent	Sp. gr.	
185	3	6.6	0.870	15.8	0.939	92.3	0.971	92.6
185	9½	10.4	0.869	21.8	0.939	92.0	1.00	88.3

We claim:

1. The process of producing alkyl aromatic hydrocarbons boiling below about 300° C. from a petroleum tar comprising a substantial amount of alkyl aromatic hydrocarbons entirely of petroleum origin which are normally found in such tar and are of higher boiling point than said alkyl aromatic hydrocarbons to be produced, which comprises treating such alkyl aromatic hydrocarbons of said tar with benzene in the presence of a metal halide catalyst at a temperature between about 80° C. and about 200° C.

2. The process of producing alkyl aromatic hydrocarbons boiling below about 300° C. from a petroleum tar comprising a substantial amount of alkyl aromatics entirely of petroleum origin which are normally found in such tar and are of higher boiling point than said alkyl aromatics to be produced, which comprises treating said petroleum tar with benzene in the presence of an aluminum chloride catalyst at a temperature between about 80° C. and about 200° C.

3. The process of producing alkyl benzenes and alkyl naphthalenes boiling below about 300° C. from a petroleum solvent tar comprising a substantial amount of alkyl aromatics entirely of petroleum origin which are normally found in such tar and are of higher boiling point than said alkyl aromatics to be produced, which comprises treating said petroleum solvent tar with benzene in the presence of an aluminum chloride catalyst at a temperature between about 80° C. and about 120° C.
